JOHN J. HALLIWELL, OF TUCKAHOE, NEW YORK, ASSIGNOR, BY MESNE ASSIGNMENTS,
TO R. HOE AND CO., INC., OF NEW YORK, N. Y., A CORPORATION OF NEW YORK

INKING MECHANISM

Application filed October 15, 1924. Serial No. 743,655.

This invention relates to certain improvements in inking mechanism for printing machines.

Inking mechanism for printing machines usually include an ink distributing cylinder or distributor to which ink is delivered in various ways. Cooperating with this distributor are a plurality of inking rolls, the function of these rolls being to grind the ink and provide an even distribution of the ink over the surface of the distributor, the distributor delivering the ink to the form member of the printing couple, usually through the medium of small rolls known as form rolls. To effect a good distribution of the ink on the distributor, a number of inking rolls have been employed. These inking rolls are small and to get a desired number have to be placed pretty close together. It has been customary to vibrate certain of these rolls, that is, a means is provided to effect a longitudinal movement of these rolls relatively to the distributor. It has been difficult, owing to the necessary close adjacency of these small rolls to vibrate them all, as it has been difficult to get the necessary parts for effecting the vibration in the small space provided.

It is the especial object of the present invention to provide an inking mechanism in which the small distributing rolls may be arranged closely adjacent so as to provide a good distribution of ink, and in which any or all of these small rolls may be vibrated, and a mechanism in which the ink distributing cylinder or drum itself is also vibrated, the vibration of the drum and certain of the rolls being in opposite directions, so that a very good distribution of the ink is effected.

A further object of the invention is to provide a construction by which this may be effected by a single cam, and in which the parts are few in number and thus simple to construct.

With these and other objects not specifically referred to, the invention consists in certain novel parts, arrangements and combinations which will be described in connection with the accompanying drawings, in which

Figure 1 is an end view, partly in section

and partly broken away, of the improved inking mechanism;

Figure 2 is a partial side view of the construction shown in Fig. 1, the view being partly in section and certain parts being omitted for the sake of clearness;

Figure 3 is a detail view on an enlarged scale, the view being taken on the irregular line 3—3 of Fig. 1, looking in the direction of the arrow, showing the parts arranged outside the press frame, and

Figure 4 is a detail view on an enlarged scale, the view being taken on the line 4—4 of Fig. 1, looking in the direction of the arrow, showing the arrangement of the parts which are located inside the press frame.

Referring now to these drawings, 1 indicates the framing of the machine, which may be of any usual or desired configuration, for supporting the parts. Mounted in this framing on a shaft 2 is one member of a printing couple, shown in the form of a cylinder 3, this cylinder being driven in any suitable manner, not shown. Cooperating with this cylinder are a pair of the usual form rolls 4, 5 supported on shafts 6, 7 suitably mounted in the side frames of the machine. Ink is supplied to these form rolls by a large ink drum or distributor 8, and this distributor receives its ink supply in any suitable way. In the particular construction illustrated, ink is supplied by means of pumps, not shown, through a pump box 9 suitably supported on a bracket 10 carried in the side frames 1. From the pump box ink is delivered through pipes, one of which is shown marked 11, to an ink rail 12 which delivers the ink to the surface of the cylinder. Cooperating with the cylinder are a plurality of ink distributing rolls marked 13, 14, 15, 16 and 17, the rolls 13, 14 and 15 being carried on shafts 18, 19 and 20 suitably supported, and the rolls 16, 17 being supported by shafts 21, 22.

In accordance with the invention, the ink distributing drum 8 and the ink distributing rolls are vibrated, and this vibration is effected so that the vibration of the drum is in an opposite direction to that of certain of the rolls. Furthermore, the small rolls are pref-

erably vibrated so that the time of vibration is different for certain of the rolls, a very good distribution of the ink being effected by this arrangement.

5 In the best constructions, furthermore, the vibration of the parts is effected by a single cam. While the specific construction for effecting this may be somewhat varied, in the particular construction shown, the ink distributing cylinder 8 is supported by a pair of heads, one of which is shown marked 23, this head being secured to the cylinder in any suitable manner, as by bolts 24. This head 23 has a short shaft 25 which is journaled in the side frame 1, before referred to, this shaft extending through the frame, as shown in Fig. 2. Mounted on this shaft and having a longitudinal movement therewith is an operating cam 26 having a cam groove 27, this cam being located inside the side frames 1, before referred to. Cooperating with this cam is a cam roll 28 mounted in the end of a bracket arm 29 fixedly secured to one of the side frames. As the cam rotates 25 the distributing cylinder 8 is thus given a to and fro vibrating movement.

In the particular construction illustrated, all the small rolls are also given a vibrating movement and this vibrating movement as to 30 certain of the rolls is in a direction opposite to that of the distributor 8. While this may be effected in various ways, in the particular construction shown, two of the small rolls, as 13 and 15, are operated by connections positioned outside the framing of the machine. As shown, the end of the shaft 25, beyond the frames, is provided with a grooved collar or sleeve 30 fixedly secured on the shaft. Working in the groove of this collar are rolls 31, 32 carried on the inner ends of rocker arms 33, 34 pivoted on a stud 35 carried in a bracket 36 secured to the side frame of the machine. The arms 33, 34 carry at their other ends rolls 37, 38 which run in grooves 39 on sleeves 40 fast on the ends of the roll shaft 18, 20, before referred to. Thus, as the operating cam 26 is shifted sidewise by the roll 28, the shaft 25 is given a sidewise movement and through the arms 33, 34 the rolls 13, 15 45 are given a vibratory movement, this movement being in a direction opposite to that imparted to the vibrating cylinder 8.

The roll 14 is also, in the particular construction illustrated, given a vibrating movement. This is effected through the cam 26. As shown (see Fig. 4), there is provided a rocker arm 41 pivoted on a stud 42 in a bracket 43 secured to the inside of the side frame 1, before referred to. This arm at one 60 end has a roll 44 which works in the groove 27 of the cam 26, before referred to, and this arm at its other end carries a roll 45 running in a groove 46 in a sleeve 47 on the end of the roll shaft.

65 In the construction illustrated, the rolls 16,

17 are also vibrated and, in the particular construction illustrated, one of these rolls, as the roll 17, is vibrated from the cam 27, and the other roll 16 is vibrated from the roll 17 and in the opposite direction thereto. While the construction for effecting this may be somewhat varied, in the particular construction illustrated, see dotted lines in Fig. 1, there is provided a rocker arm 48 pivoted on a stud 49 mounted in a bracket 50 secured to the frame of the machine. This rocker arm 48, at one end, has a roll 51 running in the groove 27 of the cam 26, and this rocker arm at its other end has a roll 52 running in a grooved collar 53, on the end of the roll shaft 80 or journal 22. Also running in the groove of this collar, is a roll 54 on a rocker arm 55 pivoted on a stud 56 in a bracket 57 secured in the side frame of the machine, this arm at its other end carrying a roll 58 running in a grooved collar 59 on the end of the roll shaft 85 or journal 21.

With this construction it will be observed that the parts operated by the cam 27 are vibrated at different times, owing to the position of the operating rolls in the cam groove, and certain of the small rolls are vibrated in a direction opposite to the direction of the drum 8. With this construction, therefore, a seesaw action is produced and a very efficient grinding and distribution of the ink on the distributor roll is effected. Furthermore, it will be observed that at no time are all of the small rolls stationary with respect to the distributor, the parts being so timed that as certain of the rolls stop at the end of their reciprocating movement other of the rolls are still being reciprocated.

Thus in the particular arrangement shown the rolls 13 and 15 vibrate in time with the distributor 8, but in opposite directions thereto; the roll 17 moves in the opposite direction to the distributor 8 but out of time therewith; the roll 16 moves in time with but in the opposite direction to the roll 17, and the roll 14 moves in the opposite direction to the distributor 8 but out of time therewith and out of time with the roll 17. Thus while the distributor 8 and the rolls 13 and 15 are dwelling at the end of their stroke, the other rolls are in vibratory motion.

The parts may be driven in any suitable or desired manner. In the particular construction illustrated, the parts are driven from the form cylinder 3. To effect this, the shaft of the form cylinder carries a gear 60 which is in mesh with an intermediate gear 61. This intermediate gear 61 is in mesh with a large gear 62, on the opposite end of the drum 8 to that shown in Fig. 2, and drives the drum. The short shaft 25 has, at its outer end beyond the frame of the machine, a gear 63 keyed thereon. This gear 63 is in mesh with a wide gear 64 fast on a stud 65. This

stud, at its inner end inside the machine frame, carries a wide pinion 66 which is in mesh with a gear 67, which is part of the cam 26, before referred to, the cam 26 thus being driven. If desired, the ink pump may be driven by a chain 68 from a shaft 69 having a beveled gear 70 in mesh with a beveled gear 71 on the stud 65, before referred to.

With the construction shown and described, a very efficient distribution of the ink is obtained on the distributor. While the invention has been shown and described in its preferred form, it will be understood that various changes may be made in its specific construction and operating mechanism of the parts without departing from the invention, as defined in the appended claims.

What I claim is:

1. In an inking mechanism, the combination of a form member, a large ink distributing member, a plurality of smaller ink distributing rolls, means moving with the distributing member for effecting a vibratory movement of the ink distributing member, and means for effecting a vibratory movement of the rolls so that certain of the rolls are vibrating out of time oppositely to the ink distributing member and substantially out of time relatively to each other.

2. In an inking mechanism, the combination of a form member, a large ink distributing member, a plurality of smaller ink distributing rolls, means for effecting a vibratory movement of the ink distributing member and certain of the rolls in opposite directions, and means for effecting the vibratory movement of other rolls so that certain of said other rolls are vibrating out of time relatively to the ink distributing member.

3. In an inking mechanism, the combination of a form member, an ink distributing member, ink distributing rolls, a shaft connected with the ink distributing member, a cam for effecting a vibratory movement of the shaft, and connections from the cam for effecting a vibratory movement of certain of the rolls in an opposite direction to that of the ink-distributing member and at different times with respect to each other.

4. In an inking mechanism, the combination of a form member, an ink distributing member, a plurality of ink distributing rolls, a cam, connections from the cam for effecting a vibratory movement of the distributing member, connections from the cam for effecting a vibratory movement of certain of the rolls, and connections operating from another point of the cam for effecting the vibration of other of the rolls.

5. In an inking mechanism, the combination of a form member, ink distributing rolls, a shaft, a cam on the shaft for vibrating the latter, connections from the cam for vibrating certain of the rolls, and connections from

the shaft for vibrating certain of the other rolls.

6. In an inking mechanism, the combination of a form member, an ink distributing member, a plurality of ink distributing rolls, means moving endwise with the distributing member for effecting a vibratory movement of the distributing member, and means for effecting a vibratory movement of the rolls so that certain of the rolls are vibrated out of time with the distributor and substantially out of time with each other.

7. In an inking mechanism, the combination of a form member, an ink distributing member, a plurality of ink distributing rolls, means for effecting a vibratory movement of the distributing member, and means for effecting a vibratory movement of certain of the rolls in the opposite direction but substantially out of time with the distributing member and out of time with each other.

8. In an inking mechanism, the combination of a form member, an ink distributor having an endwise movement, a plurality of ink distributing rolls, and means moving with the distributor for giving certain of the rolls vibratory movements relatively to the distributor in the opposite direction substantially out of time with each other.

9. In an inking mechanism, the combination of a form member, an ink distributing member, ink distributing rolls, and a single cam for effecting a vibratory movement of certain of the ink distributing rolls in opposite directions to each other and out of time with the distributor and at substantially different times with respect to each other.

10. In an inking mechanism, the combination of a form member, ink distributing rolls, a shaft, a distributing member on the shaft, a cam held against endwise movement on the shaft but rotating thereon, a fixed roll effecting endwise movement of the cam and shaft, and connections engaging the cam for vibrating certain of the ink distributing rolls.

11. In an inking mechanism, the combination with a reciprocable ink cylinder, and a plurality of distributing rolls in contact therewith, of means for reciprocating said cylinder, and means for reciprocating three of said rolls in three different ways.

12. In an inking mechanism, the combination with a reciprocable ink cylinder, and a plurality of distributing rolls in contact therewith, of means for reciprocating said cylinder, and means for reciprocating three of said rolls in three different ways, one of them always moving in a direction contrary to the motion of the cylinder.

13. In an inking mechanism, the combination with an ink cylinder, and distributing rolls in contact therewith, of means for reciprocating the cylinder, and means for reciprocating certain of said rolls so timed that

130

when one is at the end of its stroke the other will be substantially at the center of its stroke.

14. In an inking mechanism, the combination with an ink cylinder, and a distributing roll in contact therewith, of means for reciprocating the cylinder, and means for moving said roll axially a full stroke in one direction while the cylinder is moving from central position to the end of its stroke and back to central position.

15. In an inking mechanism, the combination with an ink cylinder, and a distributing roll in contact therewith, of means for reciprocating the cylinder, means for moving said roll axially in one direction while the cylinder is moving from central position to the end of its stroke and back to central position, and means co-operating therewith for reciprocating another distributing roll always in a direction contrary to the motion of the cylinder.

16. In an inking mechanism, the combination with an ink cylinder, and two distributing rolls contacting therewith and reciprocable in an axial direction, of means for reciprocating both rolls so timed that one roll completes its stroke when the other is part way through its stroke, and means for reciprocating the cylinder oppositely to the reciprocation of one of said rolls.

17. In an inking mechanism, the combination of a form member, an ink distributing member, ink distributing rolls, and means for effecting a vibratory movement of the ink distributing member and certain of the ink distributing rolls in opposite directions to each other and out of time with the distributing member and at substantially different times with respect to each other.

18. In an inking mechanism, an ink cylinder, a pair of distributing rolls, running in contact with the cylinder, and means for axially reciprocating the cylinder and the rolls in such timed relation that the axial motion of the cylinder is reversed while the rolls are moving axially.

19. In an inking mechanism, an ink cylinder, a pair of distributing rolls running in contact with the cylinder, and means for axially reciprocating the cylinder and the rolls in such timed relation that the axial motion of the cylinder is reversed while the rolls are moving axially and the axial motion of each roll is reversed while the other roll is moving axially.

20. In an inking mechanism, an ink cylinder, a pair of distributing rolls running in contact with the cylinder, and means for axially reciprocating the cylinder and the rolls in sequence and in such timed relation that the axial motion of the cylinder is reversed while the rolls are moving axially in opposite directions to each other and the

axial motion of each roll is reversed while the cylinder is moving axially.

In testimony whereof, I have hereunto set my hand.

JOHN J. HALLIWELL.
